UNITED STATES PATENT OFFICE.

EUGENE DU PONT, OF WILMINGTON, DELAWARE, ASSIGNOR TO E. J. DU PONT DE NEMOURS & CO., OF SAME PLACE.

GUNPOWDER-PRESS.

SPECIFICATION forming part of Letters Patent No. 350,048, dated September 28, 1886.

Application filed June 5, 1885. Serial No. 167,749. (No model.)

To all whom it may concern:

Be it known that I, EUGENE DU PONT, a citizen of the United States, and a resident of Wilmington, in the State of Delaware, have 5 invented a certain new and useful Machine for Compressing Explosive Compounds; and I hereby declare that the following is a full, clear, and exact description of the same, reference being had to the accompanying drawings, forming part of the specification.

In said drawings, Figure 1 is a view of my improved machine, taken in vertical section. Fig. 2 is a view of the mold-plate, showing the recesses of molds for holding the powder to be 15 compressed.

Similar letters indicate similar parts in different figures.

A A' is a frame for holding the operative parts of the machine.

20 B B' are two hydraulic pistons or rams for exerting requisite compressive force.

C C' are chambers into which water is forced to operate the compressing-pistons.

25 D D' are pipes for supplying water to the hydraulic pressure-chambers C C'. Said pipes communicate with the same pump or with pumps arranged to operate the pistons or rams equally.

In my machine it is very desirable that the 30 two pistons or rams should move and exert compressive force equally, and as machines of this character are generally of large size and great strength, because very great power is to be applied, both the pistons are of considerable weight. In order that the two pistons, if arranged in a vertical position one above the other, should act with equal pressure or be balanced, it is necessary that the pressure-chamber of the lower piston should be slightly larger 35 than that of the upper piston, if both pressure-chambers are to be supplied by one or by equally-acting pumps. This may be accomplished by enlarging the chamber of the upper piston-rod, as shown in Fig. 1, or any other 40 well-known means should be used to regulate the compressive force of the pistons, so as to equalize the same.

E is a fixed mold-plate containing a number of apertures, X X, for the reception of powder, and in which the powder is to be compressed. These apertures are generally of

prismatic form, so as to give the grains of powder formed in them a prismatic shape. One of the hydraulic rams or pistons is fitted on its upper surface with plungers G, formed to fit in the apertures X X in the plate E and move therein. These plungers correspond in size, position, and arrangement with the apertures X X in the plate E. Through the center of such plungers G run needles H, which I have shown as made movable by means of toggle-joint I, which, by the suitable connections K, is arranged to move all the pins or needles upward together through the center of the plungers G. Attached to the other arm or 65 piston are other plungers, L, also corresponding in size, number, position, and arrangement with the apertures X X for the powder in the plate E, and provided with a central hole, M, to receive the movable pins or needles H.

The operation of this machine is as follows: A quantity of powder is poured upon the plate E and swept into or otherwise placed in the apertures X X until such apertures are 70 substantially full. The lower end of the apertures are closed at this time by the ends of the plungers G. The pins or needles H do not project above the surface of the plate E, so as to prevent the easy filling of the apertures X X. When the apertures are all filled, hydraulic pressure is applied to the rams or pistons B B', and such rams or pistons move toward each other with equal compressive force. The plungers G and L enter the apertures X X on opposite sides and compress the powder between them, and at the same time the pins or needles H are raised by the toggle-joint I and its connections K, so that the pins or needles enter the holes M in the opposing plungers. The result of this operation is that the powder in the apertures is compressed with equal force at both ends, and the result is the formation of a large grain of the desired dimension and form, (cylindrical or prismatic,) 80 in which the ends of the grain, being compressed with equally-moving pistons or rams, are both hard, while the central parts of the grain are comparatively soft when the grain is removed from the molding apertures. A grain of such construction having two hard 85 ends and a comparatively soft center is of

great advantage in firing large ordnance, as it burns with rapidity from the center as well as the ends when once started, though the initial rate of combustion is slow, owing to the compacted ends.

It is obvious that the machine may be arranged with the pistons moving horizontally; but in that case the filling of the molds with powder would be much more difficult. It is also obvious that other connections may be used for moving the needles than the toggle-joint I and its connections K, the particular mechanism shown in such location not being an essential portion of my invention.

15 I contemplate constructing my machine with the needles or pins immovable, and, if desirable, I dispense with such needles or pins altogether and form solid grains.

The product of this machine is more fully

described in a pending application for Letters Patent of the United States therefor.

What I claim, and desire to secure by Letters Patent, is—

In a machine for forming grains of explosive compounds, the combination of a fixed mold-plate containing suitably-formed apertures for molding powder, two equally moving and balanced rams acting to compress the grains from both ends, and pins passing through the apertures in said mold-plate and having a longitudinal motion therein independently of said rams, substantially as and for the purposes described.

EUGENE DU PONT.
